UNITED STATES PATENT OFFICE.

ERNEST J. BRASSEUR, OF CHICAGO, ILLINOIS, ASSIGNOR TO A. B. DICK COMPANY, OF CHICAGO, ILLINOIS, A CORPORATION OF ILLINOIS.

ENVELOP-SEALING AND STAMP-AFFIXING MACHINE.

945,744.

Specification of Letters Patent. Patented Jan. 11, 1910.

Application filed March 23, 1907. Serial No. 364,125.

To all whom it may concern:

Be it known that I, ERNEST J. BRASSEUR, a subject of the King of Belgium, residing at Chicago, in the county of Cook and State of Illinois, have invented a certain new and useful Improvement in Envelop-Sealing and Stamp-Affixing Machines, of which the following is a specification.

This invention relates to machines for sealing envelopes and affixing stamps thereto.

The object of the invention is to provide a machine for this purpose which is efficient and reliable in operation, which can be run at comparatively high speed, and which is entirely automatic in its operation, the stamps and envelopes being fed successively, the envelopes sealed and the stamps affixed thereto without manipulation by the operator.

A further object of the invention is to provide a machine of this character in which the stamps are fed into the machine in the form of sheets, just as they are sold in quantities. To this end, the machine is so constructed as to receive a sheet of stamps, to feed the sheet forward, cut strips of stamps from one edge thereof successively and then feed this stamp-strip to a mechanism for severing the individual stamps therefrom and sealing them upon the envelopes.

The preferred embodiment of my invention is illustrated in the accompanying drawings, in which—

Figure 1 is a top view of the machine; Fig. 2 is a section inside one of the side-frames, the section line being indicated by the line 2—2 of Fig. 1; Fig. 3 is a similar section inside the other side-frame on line 3—3 of Fig. 1; Fig. 4 is a central section on line 4—4 of Fig. 1; Fig. 5 is a transverse section on line 5—5 of Fig. 4; Fig. 6 is a detail view of a portion of the operating mechanism; Fig. 7 is a detail view of the stamp-feeding mechanism; Fig. 8 is a detail view in section on the line 8—8 of Fig. 7; Figs. 9 and 10 are detail views of portions of the operating mechanism on lines 9—9 and 10—10 respectively of Fig. 6; Fig. 11 is a detail view hereinafter referred to, and Fig. 12 is a perspective view of one of the pairs of forwarding rollers and the lifters coacting therewith.

Referring to the drawings, the machine has a base 1 and side-frames 2 and 3 erected

thereon; the operating parts of the machine all lie between and are supported upon these side-frames, with the exception of the receiver for the unsealed envelopes, which rests upon the base 1 between the side-frames. 60 This receiver consists of a frame 4 having upright posts 5 at the corners thereof, the two posts at the sides of the frame carrying rails 6 and 7 at their upper ends. Each of these rails is inclined throughout the 65 greater portion of its length, and beyond the upper end of this inclined portion is provided with an extension the upper surface of which is concave. The rail 7 forms one side-guide for a stack of envelopes 8 (Fig. 70 4); the other side-guide 9, is adjustable toward and away from the guide 7, in order to adapt the machine for operation with envelopes of varying sizes. This guide 9 consists of a rail having integral depending 75 arms 10 carrying a member 11, which is adapted to slide back and forth upon a strip 12 extending between and secured at its ends to the sides of the frame 4. A set-screw 13 is threaded into the member 11 and is adapted to engage the strip 12 to lock member 11 and the guide 9 in any adjusted position.

Extending inwardly from one of the posts 5 at the side of the receptacle on which the rail 7 is mounted, is a stud 14 (Fig. 4) on 85 which is pivotally mounted a support 15; the other end of this support has a depending finger 16 extending through a slot in a stud 17 on the forward post 5 at that side of the receptacle, to guide the support in 90 its movements about its pivot, the stud 14. A similar support 18 is pivotally mounted upon a stud 18' extending inwardly from the side-guide 9, and the forward end of this support is similarly guided by a slotted 95 stud 17' projecting from the rail 9. The forward ends of the pivoted supports 15 and 18 rest upon a bail 19, the ends of which are pivoted upon the frame 4. An adjusting device cooperates with this bail to turn 100 it about its pivots and thus raise or lower the forward or free ends of the supports 15 and 18. This adjusting device consists of a rod 20 (Figs. 2 and 5) having a bent end 20' extending around one of the side members of bail 19 and a hand-nut 21 threaded upon the end of rod 20 and engaging the supporting frame 21' therefor to move the rod axially and thus turn the bail 19 on its pivots. The envelopes to be sealed and 110

stamped are placed upon the supports 15 and 18 and by means of the adjustment device above described the upper edge of the forward envelop may be adjusted to the desired level, regardless of the size of the envelop.

Extending between the posts 5 at the forward end of the receptacle, is a plate 22 having an upwardly extending arm 22' at 10 one side thereof. A corresponding arm 23 is secured to the forward end of the side-guide 9, so as to be laterally adjustable therewith. The supports 15 and 18 are so adjusted vertically that the flap of the end one 15 of the unsealed envelopes resting thereon will be free of plate 22 and will extend out over the same at a slight angle to the body portion of the envelop. All of the envelopes are stacked in the receptacle with their flaps toward the plate 22 so that when the forward envelop is withdrawn the next succeeding 20 one will assume this position. A follower-block 24 is adapted to move back and forth upon the rails 6 and 7, the block for this purpose having pairs of grooved rollers 24' at its sides adapted to run on the upper edges of the rails 6 and 7. This follower-block is of considerable weight and when its forward side bears against a stack of unsealed envelopes resting upon the supports 15 and 18, as shown in Fig. 4, it presses the forward envelop against the plate 22 with considerable pressure. When placing a pile of envelopes in position in the unsealed-envelop 30 receptacle, the follower 24 may be drawn back to a position in which the rear rollers 24' rest upon the concave extensions at the rear ends of the rails 6, 7, so that the follower is held in this position.

The machine may be operated manually or by any suitable power-driven devices; in the drawings, I have shown a hand-wheel 25 for this purpose. This wheel is secured upon a shaft 26 (Fig. 2) extending across 40 between the side-frames 2 and 3 and journaled in bearings therein, one end of the shaft being extended through the side-frame 2 to carry the hand-wheel 25 upon its end. The shaft 26 has a gear 26' secured thereon, meshing with a gear 27 mounted for rotation upon a stud 27' upon the side-frame 2, and gear 27 meshes with a pinion 28 similarly mounted for rotation upon a stud 28'. This pinion 28 meshes with a gear 29 secured upon a stub-shaft 29'; also secured upon the stub-shaft 29' are two cams 30 and 31. A link 32 is pivotally connected eccentrically to the outer face of the cam 31 and at its lower end is connected to a lever 33 50 pivoted at 33' to the side-frame 2. A similar lever 34 is pivotally mounted upon the opposite side-frame 3. At their forward or free ends, these levers 33 and 34 carry a pivoted flap-turning device 35 (Fig. 4) having 60 a spring 35' coiled about one of the pivots

thereof and arranged to press the upper edge of the member 35 toward the plate 22 or the body-portion of the forward envelop of the pile above the plate.

Mounted upon the end of the member 35 70 is a roller 36 adapted to travel on a suitable way 36' and held against the same by spring 35'; this way is so shaped that when the levers 33 and 34 are turned about their pivots, the upper edge of the member 35 is 75 moved vertically through a short distance until it enters between the flap and body-portion of the forward envelop and then is raised and moved away from the body-portion of the envelop, so that member 35 first 80 moves under the flap and then moves the flap out from the body-portion and turns it until it projects upwardly from the body-portion of the envelop.

Between the side-frames 2 and 3, the shaft 85 26 carries a forwarding-roller 37. Directly opposite this roller is a coöperating forwarding-roller 37', and below the latter is a roller 38. A plurality of endless belts 38' run upon the rollers 37' and 38, the periphery of 90 the roller 37' being preferably grooved circumferentially to receive these belts so as to provide a smooth surface upon the roller along the line of coaction with the roller 37. The rollers 37' and 38 are journaled at their 95 ends in bearings formed in supports 39, (Figs. 2 and 3) which are pivoted at 39' to a guard 40 secured to the side-frames. A link 41 is pivotally connected at one end to one of the supports 39 and at the other end 100 to the free end of a link 42 pivoted on a stud projecting inwardly from the side-frame 2, and mounted on the pivot connecting the links 41 and 42 is a roller 42' which bears upon the surfaces of the cam 31 on the stub-shaft 29'. Roller 42' is held in engagement 105 with cam 31 by a spring 41' (Fig. 3) on the opposite side of the machine, secured at one end to the member 39 and at the other to a stud projecting inwardly from the side-frame 3.

Mounted for rotation upon the pivot 39' of the support 39, is a gear 43 which meshes with the gear 27 and is driven thereby, and this gear 43 also meshes with a gear 43' on 115 the shaft of the forwarding-roller 37', so that rotary motion is communicated from gear 27 to the forwarding-roller 37' in any position of the supports 39 and from that roller to the roller 38 by the belts 38'.

Above the forwarding-rollers 37 and 37' is another pair of forwarding-rollers 44 and 44' carried by shafts the ends of which are journaled in bearings in the side-frames 2 and 3 and the guard 40 secured to the frames. The shaft of roller 44 carries a gear 45 which meshes with the gear 27 and the shaft of roller 44' carries a gear 45' which meshes with the gear 43, so that this pair of forwarding-rollers are driven whenever the 120 125 130

forwarding-rollers 37 and 37' are driven. These rollers 44 and 44' are preferably rubber-covered and are of sectional form, as shown in Fig. 5. The sections of the roller 44' may have the shape of spools, so as not to press upon the envelopes too hard and squeeze moisture out from under the flap. The sections at the ends of the rollers over the stationary side-guide 7 of the unsealed envelop receptacle are, however, of cylindrical shape as these sections also serve to press the moistened stamps upon the envelopes. Between the two pairs of forwarding rollers and extending between the two side-frames, is a vertically disposed plate 46, along which the envelopes are fed and which forms a guide therefor.

The moistener for the envelop flaps is mounted upon a bar 47 extending between the side-frames, and consists of a trough 48 for holding water, a wick 48' and a moistening-roller 49, to which the water is carried by the wick. The roller 49 has a soft absorbent surface and is mounted for rotation in the sides of the trough 48. At one end of the roller 49 the shaft thereof carries a pinion 49', which meshes with a gear 50 mounted for rotation upon the stud 27' adjacent to the gear 27. The trough 48 and parts carried thereby are secured in position upon the bar 47 by means of screws 50', so that they can be readily removed. Pivotally mounted upon the shaft of roller 44' and swinging loosely thereon, are two arms 51 carrying a presser-roller 52 adapted to hold the flap of an envelop against the moistening-roller 49. One of these arms 51 is extended upwardly, as shown at 51' Fig. 3, and is pivotally connected to a link 52', the opposite end of which is pivotally connected to one end of a link 52" pivoted upon the frame of the machine and carrying at its opposite end a roller bearing upon the periphery of a cam 53. The roller is held against the periphery of the cam by a spring 51" secured at one end to the link 52' and at the other to the frame. The shaft of this cam is actuated to make one revolution each time an envelop is fed through the machine in the manner hereinabove described, and in such revolution rocks the link 52" and the arms 51 and thus moves the presser-roller 52 to the left in Fig. 4 to such position that it lies over and close to the roller 49 and holds the flap of the envelop against that roller.

On the shaft of the roller 44, alongside the gear 45, is a pinion 54 meshing with an idler-pinion 54', which meshes with a gear 55 mounted on a stub-shaft 55' on the side-frame 2. This stub-shaft also carries a mutilated gear 56 and a notched disk 56'. The mutilated gear 56 is adapted to mesh with a pinion 57 secured on a shaft 58 mounted for rotation in suitable bearings secured on the side-frames. At the side of the gear 57,

is a disk 57' having a tooth 57" (Fig. 11) which coacts with the notched disk 56' on the stub-shaft 55', to lock shaft 58 against rotation after it has made one complete revolution, due to the coaction of the mutilated gear 56 and the pinion 57. Secured on shaft 58 is a finger 59, which, when the shaft is rotated, engages a stud 59' on a rock-shaft 60, one end of which is mounted for rotation in a bearing formed by countersinking the inner end of the stub-shaft 55' and the other end of which is similarly mounted in a bearing supported on the side-frame 3. A spiral spring 60' is coiled about one end of shaft 60 and arranged to rock it in the direction opposite to that in which it is rocked by the finger 59. Secured on shaft 60 are a plurality of lifters 61, adapted to be moved under the lower edge of an envelop just as that edge is passing out from between the forwarding-rollers 44 and 44' and lift the envelop to the level of the sealed-envelop receptacle. The shape of these lifters is shown in Figs. 4, 11 and 12 from which it will be seen that each has a finger adapted to rest upon the shaft of the forwarding-roller 44 between the sections of that roller. The lifters 61 are normally held in the position in which they are shown in Fig. 4 by the spring 60', but when the mutilated gear 56 engages the pinion 57 and rotates shaft 58 through one complete revolution, the finger 59 engages the stud 59' and rocks shaft 60 against the tension of spring 60' through nearly a quarter of a revolution. At the conclusion of this movement of the lifters, the fingers at the ends thereof pass through slots in the forward edge of the sealed-envelop receptacle 62, these slots being shown at 62' Fig. 1. 105

The tray 62 consists of a sheet-metal plate flanged upwardly at its rear and lateral edges, supported upon the side-frames of the machine and upon a bar 63 extending between the frames. A vertically disposed rear wall-plate 64 is adapted to move over the upper face of the tray 62 and is pressed forwardly by a spring. For this purpose, the wall-plate 64 has an integral horizontal extension at the lower edge thereof, in which are slots to receive and permit movement of a pair of screws 64' secured upon the ends of a pair of links 65 which are pivotally connected at their rear ends to the ends of a pair of similar links 65'. The rear ends 120 of these links have studs thereon passing through slots in the tray 62 and connected by a spiral spring 66. Also, the links 65' are pivotally connected at the center thereof and this pivot extends through a slot 125 in the tray 62 extending lengthwise thereof. By means of this construction, the spring 66 acts upon the links to draw them toward a position of parallelism and thus constantly press the wall-plate 64 130

forwardly upon the tray 62. At its forward edge, the tray 62 has a downwardly turned flange 67, and, directly in rear of this, a plurality of openings 67' (Fig. 1). One member of a hinge 68 is secured to the rear side of the flange 67, adjacent to each of the openings 67', and the movable member of each hinge is pressed upwardly through the opening 67' by a suitable spring.

10 The forward wall-plate 69 of the sealed-envelop receptacle is movable from a position to the right of the hinges 68 in Fig. 4 as shown by the dotted lines, to the position shown in that figure in full lines to the left of the hinges, and for this purpose is carried by arms 69' adapted to reciprocate in guides 70 formed on the side-frames. Pivotally connected to the ends of these arms are links 70', (Figs. 1 and 2) the ends of which are 20 pivotally connected, eccentrically, to disks 71 on the ends of the shaft 58. Extending between the side-frames, directly above the shaft 58, is a bar 72, having a slot therein through which extends the shank of a hand-nut 72' for securing to the bar 72, in any 25 adjusted position, a strip 73 having arms extending outwardly therefrom and carrying pivoted fingers 73' which can be turned about their pivots upwardly from the position shown in Fig. 4, but not downwardly. The vertical wall-plate 69 has openings therein, as shown in Figs. 4 and 5, through which the fingers 73' may pass when the wall-plate is reciprocated. As thus constructed, the pile of unsealed envelopes is placed in the receptacle therefor as above described and pressed forwardly therein by the follower-block 24. The drive-shaft 26 is then rotated by means of the hand-wheel 40 thereon, and through the gearing 26' 27, 28 and 29, drives the cam 31, and by means of the link 32 and levers 33 reciprocates the flap-turning member 35. This member when raised vertically catches under the flap of the forward envelop and then moves outwardly and upwardly, turning the flap about the body-portion of the envelop. As these movements progress, the cam 31 actuates link 41 to turn the members 39 about their 45 pivots 39' and thus move the rollers 37' and 38 away from the roller 37. At the same time, the rollers 37' and 38 are rotated by means of the gears 27, 43 and 43', and the belts 38'. The end of the flap of the envelop, when turned outwardly by the member 35, is caught by the belts 38' and carried upwardly thereby until it lies in substantially the same plane as the body-portion of the envelop. The rollers 37' and 38 are then 50 moved to the right in Fig. 4 by the spring 41 (Fig. 3), this movement being permitted by the cam 31, and the end of the envelop flap is gripped between the forwarding-rollers 37 and 37'. The rotation of these rollers being 55 continued by the gearing as above described,

the envelop is drawn upwardly from the envelop pile in the receptacle and passed upwardly along the plate 46.

As the body-portion of the envelop enters between the forwarding-rollers 37 and 37', 70 the flap, being then released turns at a slight angle to the plane of the body-portion and passes between the moistening-roller 49 and the presser-roller 52, it being guided, if necessary by the edge of the moistener tray, and 75 when a portion of the body of the envelop has passed between the rollers 37 and 37' the entire gummed portion of the flap has passed between the moistening and pressing rollers. The roller 52 is then moved to the left in Fig. 80 4 by the cam 53, as hereinafter described, to cause the gummed portion of the flap to move down upon the roller 49, which is kept moist by the wick 48' and water supply in the trough 48. The pressure of the roller 52 upon the flap is very light, it being only necessary to insure good contact of the gummed portion of the flap with the moistening-roller 49. The moistening-roller 49 is rotated 85 throughout this movement of the envelop by gear 50 and pinion 49', this rotation of the roller insuring proper moistening of the gum upon the flap. The continued rotation of the forwarding-rollers 37 and 37' causes the body-portion of the envelop to move vertically upward along the plate 46 and between that plate and the presser-roller 52, the flap of the envelop being drawn from between the presser-roller and the moistening-roller as the upward movement of the body-portion 90 progresses. Finally, the upper edge of the envelop is gripped between the forwarding-rollers 44 and 44', and the envelop is carried along in its upward movement thereby. The pressure of these two forwarding rollers upon 100 the envelop need not be sufficient to effect a reliable sealing of the envelop, this sealing being performed in the sealed-envelop receptacle. As the body-portion of the envelop is gripped by the forwarding-rollers 105 44 and 44', the forward wall plate 69 of the receptacle is in the forward position, as indicated by the dotted lines in Fig. 4, so that the envelop can pass up in rear of this plate. Just as the lower edge of the envelop 110 passes from between the rollers 44 and 44', the mutilated gear 56 comes into mesh with the pinion 57 and thus actuates shaft 58 to make one revolution. At the beginning of this revolution, the member 59 engages the 115 stud 59' on shaft 60 and rocks that shaft against the tension of spring 60', this rocking movement of shaft 60 causing the fingers 61 to turn about the axis of the shaft as a pivot. In making this turning movement, 120 the fingers at the lower ends of the lifters 61 take under the lower edge of the envelop and raise the envelop until the fingers pass through the slots 62' in the plate 62. As the 125 turning movement of shaft 58 continues, the 130

wall-plate 69 is moved rearwardly by means of the disks 71, links 70' and arms 69', and carries the envelop with it to the position shown in full lines in Fig. 4. As the wall-plate 69 is thus moved, the envelop engages the fingers 73' and the movable members of the hinges 68 and turns these parts upon their pivots, but as soon as the envelop at the rear side of plate 69 passes them they return to their initial positions, the fingers 73' under the influence of gravity and the movable members of the hinges 68 under the tension of their springs. As the one revolution of shaft 58 is completed, the plate 69 is returned to its initial position, that shown in dotted lines in Fig. 4; but the envelop is not returned with it, as its lower edge is caught by the hinges 68 and its upper edge by the fingers 73'. As soon as the wall-plate 69 has moved the envelop upon the plate 62, the stud 59' is released by the member 59 and the rock-shaft 60 carrying the lifters 61 is then returned to its original position by the spring 60', the fingers of the lifters then resting upon the shaft of roller 44 between the sections of that roller. All the parts are then in position to receive and forward the next succeeding envelop. As the pile of envelops upon the plate 62 increases, the rear wall-plate 64 is moved backward against the tension of spring 66, and this spring at all times presses plate 64 forward and exerts sufficient pressure upon the envelops to insure effectually sealing them.

The stamps are affixed to the envelops as they pass between the rollers 44 and 44'. In order to guard against wasting stamps, I provide means for controlling the actuation of the stamp-feeding and affixing mechanism, such that this mechanism will be actuated only when an envelop is in position to be fed through the machine. This means consists of a feeler 74 lying between the side frames directly over the forward envelop in the unsealed-envelop receptacle and adapted to reciprocate unrestrictedly in which case the stamp-affixing mechanism will not operate, or, on being reciprocated, to come into engagement with the flap of the forward envelop when the latter has been turned by the flap-turning member 35 and, by having its movement restricted thus, to permit the stamp-affixing mechanism to operate. Along one edge of feeler 74 are a number of grooves (Fig. 6) to receive the belts 38' at the end of the movement of the feeler to the left in Fig. 2 when that movement is unrestricted. Feeler 74 is carried by arms 74' pivotally mounted upon the side-frames of the machine, and one of these arms (that shown in Figs. 2 and 9) is extended upwardly beyond its pivot and has a spring 75 connected to its end, the other end of the spring being secured to a stud upon the side-frame. The lower end of this arm 74' is pivotally

connected to a link 76, the other end of which is pivotally connected to a link 76', the other end of which is carried by a short shaft 76² rotatable in an opening in side-frame 2. Stud 76² may have a handle 76³ secured thereon for restricting the movement of the feeler manually in starting or testing the machine. On the link 76' is a roller 77, which bears upon the periphery of the cam 30. The link 76 has an offset 77 thereon. The side-frame 2, or a member secured thereto, has a hub 77' (Fig. 6) formed therein, in which a short rod 78 is adapted to reciprocate, and this rod has a notch 78' adapted to receive the offset 77. A spring 79 is secured at one end to a stud on the rod 78 and at the other end to the hub 77', so that it normally holds rod 78 in such position that the slot 78' therein is in line with the offset 77, and a slot in the hub, further movement of the rod under the influence of the spring being prevented by the head of the rod engaging the end of the hub. It will be seen that as the machine is operated, cam 30 is rotated and by means of the links 76' and 76 the feeler 74 is reciprocated. If the movement of the feeler is unrestricted, the offset 77 will enter the slot in the stud 78 each time the feeler 74 moves toward the belts 38'. However, if the flap of an envelop has been turned about the body of the envelop so that it lies in the path of the feeler 74, the movement of the latter will be arrested before the offset 77 enters slot 78'. In the former case, rod 78 is held against longitudinal movement in hub 77' and in the latter case it is free to move.

Pivotedly connected to the inner end of rod 78, is a clutch-lever 80, (Figs. 6 and 9) the opposite end of which is bifurcated and enters a peripheral groove in a clutch-member 80' loose upon a shaft 81, one end of which is mounted for rotation in a bearing formed by counter-sinking the inner end of stub-shaft 29', and the other end of which is similarly mounted in a bearing in the side-frame 3. The clutch-member 80' has a projection 82 thereon adapted to be engaged by a stud 82' on the inner side of gear 29. The clutch-lever 80 also carries roller 83 adapted to ride upon a cam surface 83' formed on the inner face of gear 29. Clutch-member 80' has fingers thereon adapted to enter slots in a sleeve 84 which is secured upon shaft 81. The end of sleeve 84 toward the clutch-member 80' is countersunk to receive a spring 84' which presses the clutch-member 80' toward the gear 29. This spring is of greater power than the spring 79. For this reason, when the offset 77 enters the slot 78' in the rod 78 at times when there is no envelop flap to restrict the reciprocation of the feeler, rod 78 is held against movement and roller 83, riding up the cam surface 83' on gear 29 as the latter is rotated, causes clutch-

lever 83 to be turned on its pivotal connection to rod 78, and this lever, when thus turned, moves clutch-member 80' toward sleeve 84, so that the stud 82' on gear 29 passes the projection 82 on the clutch-member without engaging the same, and shaft 81 therefore remains at rest; if, however, the feeler is arrested in such position that the offset 77 does not enter notch 78', this movement of clutch-member 80' will not take place, but instead the spring 84' will hold clutch-member 80' against the face of gear 29, and when roller 83 rides up the cam surface, the floating clutch-lever 80 will be turned so as to move rod 78 inwardly of the machine in its hub 77'. In this latter case, as gear 29 rotates, the stud 82' thereon will engage the projection 82 on the clutch-member 80', and this member being locked with the sleeve 84, will cause shaft 81 to rotate. The shaft 81 will make one complete revolution, at the end of which time a similar movement of the parts will take place, the presence of the envelop flap in the path of the feeler determining whether or not the rotation of shaft 81 will be continued, and the rotation of shaft 81 being continuous if an envelop flap is turned at each upward movement of member 35.

Secured on shaft 81, is a cam 85 (Figs. 6 and 10) and co-operating therewith is a roller 85' carried by an arm 86 secured on a shaft 86' which is mounted for rotation in suitable bearings on the side-frames. Shaft 86' carries a ratchet wheel 87 having ratchet teeth on substantially half of its periphery, preferably ten in number. These teeth are engaged by a spring-pressed pawl 87' carried by the arm 86. Also secured on shaft 86' is a mutilated gear 88 having gear teeth over half of its periphery. This mutilated gear is adapted to mesh with a similar mutilated gear 88' secured on stub shaft 29' at the side of the gear 29. These mutilated gears are so positioned that when shaft 86' has been turned step by step by the pawl-and-ratchet mechanism as far as it can be so turned, the gear 88 is in position to be engaged by the gear 88' and is so engaged when the latter is brought around by shaft 29', the rotation of shaft 29' causing shaft 86' to turn through substantially half a revolution, and bringing the pawl-and-ratchet mechanism to the position for further operation. Loose on shaft 86' is a sleeve 89 lying between two collars 90 and 90', which are secured upon the shaft. A floating clutch-lever 91 is bifurcated at its ends and at one end is pivotally connected to the sleeve 89. The bifurcated arms at the other end of the lever extend into a peripheral groove in a clutch-member 91', which is splined upon the shaft 81 and normally drawn toward the cam 85 by a spring 92.

This clutch-member has a stud 92' on one side thereof, adapted to engage a stud 93 on one side of a cam 93'. The clutch-member 91' is moved in one direction or the other by raised portions formed on the collars 90, 90', which are adapted to alternately engage rollers 94 on the lever 91 (Figs. 4 and 6). The cam 93' is extended on the side opposite that carrying the stud 93, and at the end of this extended portion has a projection 95 (Figs. 6 and 7) formed thereon, adapted to reciprocate a block 96.

Secured on shaft 86' is a disk 95' having a notch cut therein into which the end of the block 96 may move when the block is engaged by the raised portion 95. This disk 95' forms a locking-plate to prevent the reciprocation of the block 96 except at the proper time. Shaft 86' is extended beyond its bearing and immediately inside the side-frame 3 carries a crank 97 having pivotally connected thereto a link 97' which at its other end is pivotally connected to a gear-sector 98 pivotally mounted upon the side frame 3. The gear-teeth of sector 98 mesh with those of a pinion 98' carried by a shaft 90 mounted for rotation upon an auxiliary frame 111 secured to the side-frame 3 and this shaft carries a gear 99 meshing with a pinion 99' on a similarly mounted stub-shaft 100, which at its inner end carries a bevel-gear 101 meshing with a bevel-pinion 102. This pinion is secured upon the end of a shaft 103 mounted for rotation in suitable bearings formed in the auxiliary frame, the frame and shaft being disposed at an incline as shown in Fig. 7. Shaft 103 has a spiral groove cut therein (Fig. 7) and extends through an opening in a block 104, this block being provided with a stud entering the groove in shaft 103, such that rotation of the shaft causes movement of the block axially thereon. Block 104 has a cutting-roller 105 mounted for rotation in a bearing therein, the shaft of which carries a pinion 106 meshing with a rack 107 formed on the under side of the top plate 108 of the auxiliary frame. Extending upwardly from block 104 at the edge of the plate 108, is an arm 109 carrying at its upper end a second cutting-roller 110, adapted to coact with roller 105.

Mounted for rotation upon the inner side of the plate 111 of the auxiliary frame, are a plurality of rollers 112 shaped as shown in Fig. 8 and each having a gear formed upon the end thereof. These rollers are arranged in line on an incline parallel to the shaft 103. Between each pair of adjacent rollers is a pinion 113 mounted on a suitable stub-shaft and meshing with the gears on the two rollers, so that all of the rollers rotate simultaneously. The shaft of the lowest one of the rollers 112 is extended through

the plate 111 and carries on its end a pinion 114 (Fig. 3) meshing with a pinion 115 carried by a suitable stub-shaft, and this pinion in turn meshes with a pinion 116 similarly mounted on the stub-shaft on which the lever 52² is mounted. Fixed to the side of pinion 116 is a disk 117 having a tooth as shown.

Secured on shaft 81 (Fig. 6) are a muted gear 118 and a notched locking plate 119, the teeth of gear 118 being adapted to mesh with those of pinion 116 and the locking-plate 119 being adapted to coact with the toothed-disk 117 to prevent rotation of pinion 116 after gear 118 has passed out of mesh therewith. Thus when gear 118 engages pinion 116, all of the rollers 112 are rotated by means of the train of gearing 116, 115, 114, the gears fixed to the rollers 112, 20 and the pinions 113. Directly underlying each of the rollers 112, is a similar roller 120, each of these rollers being carried by a small bell-crank lever 121 pivoted upon the plate 111. Each of the rollers 120 is provided with 25 a gear 122 at the end thereof (Fig. 8) meshing with the gear on the roller 112 directly overlying it. The downwardly extending end of each of the bell-crank levers 121 enters a notch in a bar 123, to which is secured 30 the block 96, the latter extending through a slot in the bottom of the auxiliary frame of the rollers and being movable in said slot. This end of each of the bell-crank levers is also connected by a spring 124 with a stud 35 on the casing, these springs serving to turn the bell-crank levers on their pivots and thus press the rollers 120 upwardly toward the rollers 112, when permitted to do so by bar 123. A U-shaped flat spring 124' bears at 40 one end on the end of bar 123 and at the other end on the end-member of the auxiliary frame, and serves to move bar 123 and block 96 secured thereto in the opposite direction to that in which they are moved by the cam 45 projection 95. The lowermost roller 120 is carried by a lever 125 similar to the bell-crank levers 121 except that it is not provided with a downwardly extending end; instead, this lever has a block 126 secured 50 thereto, having a pin 127 threaded into an opening therein, the end of this pin engaging the upwardly turned end 128 of the bar 123. Block 126 has a projection which takes over the projection 128 but is separated therefrom 55 by a short space, this space being adjustable by turning the pin 127 in its opening in block 126. Each of the rollers 112 and 120 may have at the end thereof and between the roller and its driving gear a circumferential 60 groove therein and a strip 120' (Fig. 8) may be so supported as to extend through these grooves opposite the line of engagement of the sets of rollers 112 and 120 to preclude a stamp-strip from moving laterally and being

caught in the gearing. The auxiliary frame 65 supporting these rollers is formed to provide a support for a removable moistener for the stamps. This moistener consists of a water-trough 129 having a roller 130 mounted therein, the surface of this roller being covered with rubber and engaged by the rubber-covered surface of a roller 131 directly overlying it and being above the level of the water in the trough. Overlying the roller 131 is a small roller 132, preferably provided 70 with a corrugated periphery and driven by frictional contact with the roller 131. On the shaft of the roller 131 and fixed to the roller is a gear meshing with a gear 133 adapted to mesh with a gear 134 fixed to a 75 roller 135 having a knurled surface, this roller being mounted for rotation in a hanger depending from the auxiliary frame 111. The gear 134 meshes with a gear 136 on the end of the shaft of the forwarding-roller 44. 80 The gearing is so constructed that rollers 44 and 135 rotate at a somewhat higher speed than the rollers 112 and 120, so that when a stamp strip is fed along by the rollers 112 and 120 until the stamp at the end of the 85 strip is gripped by the rollers 44 and 135, this end stamp will be torn from the strip. The stamp will then be forwarded by rolls 44 and 135 to the surface of roll 131, which, being quite moist due to its engagement with 90 roller 130, serves to moisten the gummed surface of the stamp, such moistening being assured by the roller 132 which presses the stamp against the surface of roller 131. As 95 the stamp moves out between rollers 131 and 132, it is guided upwardly by a finger 137 on the trough 129 and its edge is projected beyond the end of this finger just as an envelop 100 is moved vertically upward along the side of trough 129. The stamp is thus taken up by 105 the envelop and is pressed thereon by the forwarding-rollers 44 and 44'. A door 200 may be provided mounted on a hinge, as shown in Fig. 5, in position to close an opening in the side-frame 3 through which opening 110 the moistener for the stamps may be withdrawn for inspection and refilling of the water reservoir.

Extending between the side-frame 2 and the auxiliary frame, is a rod 138 (Fig. 4) 115 on which a stamp-tray 139 is adapted to move toward and away from the rollers 112 and 120. At one of its lateral edges, this tray is provided with an upwardly extending flange 140 and at its forward edge it is 120 serrated to correspond with the pair of rollers 112 and 120. Pivotaly mounted on a rod supported at one end by a bracket 141 and at the other by the flange 140, is a gripper-plate 142, provided with an operating 125 handle 143. The forward edge of this plate is also serrated as shown in Fig. 1, and a spring 147 is provided coiled about the sup-

porting rod of the plate and arranged to press the forward edge thereof down upon the support 139 for the sheets of stamps. Pivotally connected to the auxiliary frame, 5 as shown in Fig. 4, is a link 144, the free end of which is pivotally connected to a link 145 pivoted on the bottom of the plate 139. Link 144 carries a roller 146, which enters the groove in the cam 93'.

10 The operation of the mechanism for sealing the envelopes has been above described. The stamps are affixed to the envelopes as they pass between the forwarding-rollers 44 and 44'. The operation of the mechanism 15 for accomplishing this will now be described. A pile of sheets of stamps are placed upon the tray 139. These are sheets of a hundred stamps each, the stamps being in ten rows, ten in each row, as postage stamps are sold 20 in large quantities. The operator moves the top stamp-sheet forward until its edge is gripped between the serrated fingers on the edges of the plates 142 and 139. The handle is then turned to operate the machine. As 25 above described, the feeler 74, is reciprocated once for each upward movement of the flap-turning member 35. If a flap has not been turned by member 35, the movement of feeler 74 is unrestricted, the offset 77 enters the 30 notch in rod 78, and, as gear 29 rotates, the cam thereon shifts the clutch-member 80' to such position that the projection thereon is out of the path of stud 82' and shaft 81 remains at rest, the parts being then in the 35 relation shown in Fig. 6. If the feeler 74 encounters an envelop flap and is arrested thereby, offset 77 does not enter that notch and the cam on gear 29 operates to move rod 78 in its bearing but does not move clutch- 40 member 80' and the projection thereon is engaged by stud 82', so that shaft 81 is turned through one revolution. One or the other of these two movements of the clutch-lever 45 member 80' takes place each time the flap-turning member 35 and feeler 74 are operated, so that if a flap is turned at each upward movement of the member 35, the rotation of shaft 81 is continuous.

In starting the operation of the machine, 50 the envelopes would not be fed through the machine and sealed until the stamps had been fed along to positions for affixing to the envelopes but operation of the stamp-feeding mechanism can be secured without 55 feeding envelopes through the machine by holding the free end of handle 76' in a raised position until the stamps have reached the proper positions. This being done, shaft 81 will turn when the machine is operated. 60 Now suppose that the raised portions on sleeves 90 and 90' hold lever 91 at the beginning of the operation in such position that the stud 92' on clutch-member 91' lies in the path of stud 93 on cam 93', that the

notch in the cam 93' is opposite the end of block 96, and that the block 104 carrying the cutters is at the upper end of its inclined path of movement. As the rotation of shaft 81 begins, cam 93' is locked to the shaft and the raised portion 95 at the end of this cam engages the block 96 and moves it to the right in Fig. 7, this block carrying with it the rod 123 against the tension of spring 124' and rod 123 turns all of the bell-crank levers 121 on their pivots so as to 70 carry the lower line of rollers 120 away from the upper line of rollers 112 against the tension of the springs 124, such movement of block 96 being permitted by cam 95'. While rollers 120 are held in this position, the cam 93' actuates link 144 to move the entire stamp-tray 139 forward until the edge of the sheet of stamps between the fingers at the forward edge of the tray lies between the two lines of rollers 112 and 85 120. While in this forward position, the raised portion 95 on cam 93' passes beyond the projection on the block 96 and the springs 124 and 124' may then force rod 123 and block 96 back to their original positions, thus permitting the bell-crank levers 121 to be turned on their pivots by springs 124 and to carry rollers 120 upwardly until they grip the edge of the sheet of stamps between them and the rollers 112. Cam 93' 95 then moves tray 139 back to its original position. At this time the mutilated gear 88 is in position to be engaged by the mutilated gear 88', and just as the tray 139 is retracted, gear 88' engages gear 88 and rotates shaft 86' through one-half of a revolution. This operates through crank 97, link 97', sector-gear 98 and the gears driven therewith; to rotate the rod 103 and the latter by means of the spiral groove therein, moves 100 the cutter-block 104 from the upper end of its path of movement down to the lower end; during such movement of the block, the pinion 106 and rack 107 operate to rotate the lower cutter-roller 105. The cutter-rollers thus cut the row of stamps at the edge of the stamp sheet from the sheet, this strip of stamps being held between the two lines of rollers 112 and 120. As the cutter-block reaches the end of its downward movement, the mutilated gear 118 comes into mesh with the pinion 116 and, through the pinions 115 and 114, the gears on the rollers 112 and 120 and the pinions 113 meshing therewith, causes all of the rollers 112 and 120 to be rotated enough to feed the stamp-strip until the end stamp thereof passes in 115 between the rollers 44 and 135. These rollers are constantly rotating as the machine is operated, and as the rollers 112 and 120 come to rest, these rollers sever the end stamp from the strip and forward it to the roller 131. The surface of this roller is kept 120 125

moist by the roller 130 and moistens the gummed surface of the stamp and then forwards it between the roller 132 and finger 137. This finger guides the stamp upwardly 5 against the advancing envelop and the stamp is pressed upon the envelop by roller 44.

After shaft 86' has completed the half revolution and the mutilated gear 88 has passed out of the path of movement of the 10 teeth of mutilated gear 88', the pawl 87' is in position to engage the teeth of ratchet 87 and at each revolution of shaft 81, cam 85 actuates arm 86 to cause pawl 87' to actuate ratchet 87 the distance equal to the length 15 of one tooth. Shaft 86' is thus turned through a half revolution in as many steps as there are teeth on ratchet 87, and by means of crank 97 and link 97' sector 98 is turned upon its pivot in the opposite direction to that in which it was moved as 20 above described. Thus, rod 103 is rotated in the opposite direction and the cutter-block 104 is moved upwardly in a series of steps, such upward movement merely returning it 25 to the position which it formerly occupied in order that it may cut from the sheet another line of stamps when the sheet has been forwarded to bring its edge between the two lines of rollers. Each of these step-by-step 30 movements takes place when shaft 81 makes a complete revolution and shaft 86' a portion of a revolution corresponding to the length of one of the ratchet teeth and during each of such revolutions of shaft 81 the mutilated gears 88 and 88' come into mesh and 35 the parts are again actuated as above described to feed the stamp-sheet forward to insert another strip between rollers 112 and 120 and then sever this strip from the sheet. 40 45 When bar 123 is moved to the right in Fig. 7 against the tension of spring 124', the roller 120 at the lower end of the line is not moved away from the roller directly overlying it immediately as are the other 50 rollers 120, due to the slight separation of the projection 128 on bar 123 and the projection on block 126. The end pair of stamp-feeding rollers are thus pressed together so that they hold the last stamp of 55 the stamp-strip until the forward edge of that stamp has been gripped by the rollers 44 and 135, and by means of the screw 127 the separation of these projections can be so adjusted that this end pair of rollers will 60 hold the stamp right up to the time when they must be separated to permit the edge of the stamp-tray 139 to enter between them.

I do not wish to be understood as limited to the construction which I have herein

shown and described, as this may be modified in many ways while still retaining some or all of the features of my invention; also I wish it understood that though I have described the machine as adapted particularly for affixing stamps upon envelops, it is applicable also for use in affixing labels of various kinds, as for instance, affixing address labels to newspapers and other packages. All such modifications I consider within the scope of my invention and I aim 75 to cover them by the terms of the claims appended hereto.

Having described my invention what I claim and desire to secure by Letters Patent of the United States is:

1. The combination of stamp-affixing mechanism, a support for a pile of envelops, means for turning the flap of an envelop, and means coacting with said flap when turned for controlling the operation of said 85 stamp-affixing mechanism, substantially as described.

2. The combination of a stamp-affixing mechanism, a support for a pile of envelops, means for turning the flap of an envelop, 90 a reciprocating feeler and means dependent upon the coaction of said feeler and flap for controlling the operation of said mechanism, substantially as described.

3. The combination of a stamp-affixing mechanism, a support for a pile of envelops, a flap-turning member, means for reciprocating the same to turn the flaps of the envelops on said support successively, a feeler, means for operating the same, and 100 means dependent upon the coaction of said feeler and the flap of an envelop for controlling the operation of said mechanism, substantially as described.

4. The combination of stamp-affixing 105 mechanism, a support for a pile of envelops, a flap-turning member, means for reciprocating the same to carry its edge between the flap and body-portion of an envelop and then move away from the body-portion to 110 turn the flap relatively thereto, and means coacting with said flap when turned for controlling the operation of said stamp-affixing mechanism, substantially as described.

5. The combination of stamp-affixing 115 mechanism, a support for a pile of envelops, means for turning the flap of an envelop, means coacting with said flap when turned for controlling the operation of said stamp-affixing mechanism, means for forwarding 120 the envelop and sealing devices for sealing the envelop flap, substantially as described.

6. The combination of stamp-affixing mechanism, a support for a pile of envelops, a support for the stamped envelops, means 125 for feeding the envelops successively by a continuous movement from said first-named support to the last-named support, a feeler,

means for operating the feeler to carry it into coaction with the envelopes, and means actuated by said feeler for controlling the operation of said stamp-affixing mechanism, 5 substantially as described.

7. The combination of stamp-affixing mechanism, a support for a pile of envelopes, a flap turning member, means for operating the same to turn the flaps of envelopes successively, and a reciprocating feeler adapted to coact with the flaps of the envelopes when the same are turned, said feeler permitting said stamp-affixing mechanism to operate when it engages an envelop and preventing 15 such operation when it does not engage an envelop, substantially as described.

8. The combination of stamp-affixing mechanism, a support for a pile of envelopes, means for feeding envelopes from said support, a moistener for the envelop flaps, sealing devices for sealing the envelopes, a feeder adapted to coact with the envelopes and means for reciprocating the same, the engagement of said feeler with an envelop controlling the operation of said stamp-affixing mechanism, substantially as described.

9. The combination of stamp-affixing mechanism, a support for a pile of envelopes, means for feeding the envelopes therefrom, 30 a feeler independent of said feeding means, means for operating the feeler to carry it into coaction with the envelopes while the latter are being forwarded by said feeding means, and means actuated by said feeler 35 for controlling the operation of said stamp-affixing mechanism, substantially as described.

10. The combination of stamp-affixing mechanism, a support for a pile of envelopes, 40 means for feeding the envelopes therefrom, a feeler independent of said feeding means, means for reciprocating the feeler, said feeler being adapted to have its reciprocatory movement limited by the envelopes while the latter are being forwarded by said feeding 45 means, and means actuated by said feeler for controlling the operation of said stamp-affixing mechanism, substantially as described.

50 11. The combination of stamp-affixing mechanism, a support for a pile of envelopes, a support for the stamped envelopes, means for feeding the envelopes successively by a continuous movement from said first-named 55 support to the last-named support, mechanism for feeding stamps successively to said affixing mechanism from sheets consisting of a plurality of rows of stamps and a plurality of stamps in each row, and means coacting with the envelopes fed by said envelope-feeding means for controlling the operation of said stamp-affixing mechanism, substantially as described.

60 12. The combination of a support for a

pile of envelopes, means for turning the flaps 65 of the envelopes successively, feeding devices for the envelopes, mechanism for feeding stamps successively from sheets consisting of a plurality of rows of stamps and a plurality of stamps in each row, a movable 70 feeler and operating devices therefor, and means dependent upon the coaction of said feeler and an envelop flap for controlling the operation of said stamp-feeding mechanism, substantially as described. 75

13. The combination of a support for a pile of envelopes, means for turning the flaps of the envelopes successively, feeding devices for the envelopes, mechanism for feeding stamps successively from sheets consisting of 80 a plurality of rows of stamps and a plurality of stamps in each row, a feeler, means for reciprocating the same, and means dependent upon the coaction of said feeler and an envelop flap for controlling the operation 85 of said stamp-feeding mechanism, substantially as described.

14. The combination of a support for a pile of envelopes, means for turning the flaps of the envelopes successively, stamp-feeding 90 means for feeding stamps successively from sheets consisting of a plurality of rows of stamps and a plurality of stamps in each row, stamp-affixing mechanism, and means coacting with the flaps of the envelopes when 95 turned for controlling the operation of said stamp-affixing mechanism, substantially as described.

15. The combination of a support for a pile of envelopes, means for turning the flaps of the envelopes successively, automatic feeding and forwarding devices for the envelopes, mechanism for feeding stamps successively from sheets consisting of a plurality of rows of stamps and a plurality of stamps 105 in each row, devices dependent upon the flaps of the envelopes when turned for controlling the operation of the stamp-feeding mechanism, and means for affixing stamps to the envelopes, substantially as described. 110

16. In a stamp-affixing machine, two rollers, a feeder for a stamp-strip and means for automatically operating said feeder to insert a stamp-strip between said rollers, bringing the rollers together upon the strip, 115 operating the rollers intermittently to feed the strip step by step between them, and separating the rollers to receive a new strip, substantially as described.

17. In a stamp-affixing machine, two rollers, a feeder for a stamp-strip, means for automatically separating said rollers, operating said feeder to insert a stamp-strip between the rollers, bringing the rollers together upon the strip and operating the rollers to feed the strip, a moistener coacting with the stamps so fed, and means for affixing the stamps, substantially as described. 125

18. In a stamp-affixing machine, two rollers between which the end row of a sheet of stamps is adapted to be inserted, a cutter movable in the direction of the length of said row, means for moving the cutter to sever the row of stamps between said rollers from the sheet, and means for returning said cutter to initial position step by step, substantially as described. 65
19. In a stamp-affixing machine, two rollers between which the end row of a sheet of stamps is adapted to be inserted, a cutter movable in the direction of the length of said row, means for feeding the sheet of stamps intermittently, means for moving the cutter to sever the row of stamps between said rollers from the sheet, and means for returning said cutter to initial position step by step and simultaneously rotating said 70 rollers, substantially as described. 75
20. In a stamp-affixing machine, two rollers, a feeder, means for operating the same to insert a stamp-sheet between said rollers, a cutting device, means for moving said device in the direction of the length of the stamp-strip between said rollers, and means for rotating said cutting device in such movement to sever the stamp-strip between the rollers from the remainder of the sheet, substantially as described. 80
21. In a stamp-affixing machine, two rollers, a feeder for a stamp-strip, and means for automatically separating said rollers, moving the feeder to insert a stamp-strip between the rollers, moving the rollers together to grip the strip, withdrawing the feeder and operating the rollers intermittently to feed the stamp-strip step by step between them before separating the rollers again to receive another strip, substantially as described. 85
22. In a stamp-affixing machine, two rollers, a feeder for a stamp-sheet, means for automatically separating said rollers, operating the feeder to insert a stamp-strip between the rollers and bringing the rollers together upon the strip, means for cutting the strip from the sheet while the strip is held by said rollers, and means for operating the rollers intermittently to feed the strip step by step between them before separating the rollers again to receive another strip, substantially as described. 90
23. In a stamp-affixing machine, means for forwarding envelops through the machine, a support for a sheet of stamps, stamp-feeding rollers, a feeder for the stamp sheet, means for operating the feeder to conduct the end of the sheet between said rollers, means for severing the strip of stamps between the rollers from the sheet, means for operating said rollers to feed the strip of stamps, a pair of rollers rotating at higher speed than said rollers for severing the in- 95
- dividual stamps, a stamp moistener and means for rolling the stamps upon the envelops as the envelops pass through the machine, substantially as described. 100
24. In a stamp affixing machine, means for forwarding envelops through the machine, a support for a sheet of stamps, stamp-feeding rollers, a feeder for the stamp-sheet, means for operating the feeder to feed the end strip of the sheet between said rollers, means for severing the strip of stamps between the rollers from the sheet, means for operating said rollers to feed the strip of stamps, means for severing the individual stamps of the strip, a stamp moistener and means for rolling the stamps upon the envelops as the envelops pass through the machine, substantially as described. 105
25. In a stamp-affixing machine, a support for a stamp sheet, a pair of rollers, means for inserting the edge of said sheet between said rollers, means for severing the stamp-strip between the rollers from the sheet, means for operating said rollers to feed the stamp strip, a second pair of rollers between which the stamp strip passes, means for rotating the last named pair of rollers at higher speed than said first named pair, to sever the individual stamps of the strip, a stamp-moistener, and a roller to which the stamps are fed by said rollers adapted to roll the stamps upon the envelops, substantially as described. 110
26. In a stamp-affixing machine, a support for a stamp sheet, a pair of rollers, means for separating said rollers, inserting the edge of said sheet between the rollers and bringing the rollers together upon the sheet, means for severing the strip between the rollers from the sheet, means for operating said rollers to feed the strip, a second pair of rollers between which the stamp strip passes, means for rotating said last named pair of rollers at higher speed than said first named pair to sever the individual stamps of the strip, a stamp-moistener, and a roller to which the stamps are fed by said rollers adapted to roll the stamps upon the envelops, substantially as described. 115
27. The combination of means for feeding envelops successively along a predetermined path, a support for a stamp-sheet consisting of a plurality of rows of stamps and a plurality of stamps in each row, means for severing the stamps of said sheet and feeding them successively along a path intercepting said envelop path, a moistener for the stamps, a roller located at the junction of said paths adapted to roll the stamps upon the envelops, and means for controlling the operation of the stamp-feeding means dependent upon the envelops, substantially as described. 120
28. The combination of a support for a 125

pile of envelops, means for feeding envelops successively from said support along a pre-determined path by a continuous movement, a support for a sheet of stamps consisting of a plurality of rows of stamps and a plurality of stamps in each row, means for severing the stamps of said sheet and feeding them successively along a path intercepting said path, a pair of rollers located at the junction of said paths, one on either side of the envelop path and adapted to roll the

stamps upon the envelops, and means actuated by the envelops for controlling the feeding of the stamps, substantially as described.

M. H. BURKART,
W. A. WATERBURY.

Correction in Letters Patent No. 945,744.

It is hereby certified that in Letters Patent No. 945,744, granted January 11, 1910, upon the application of Ernest J. Brasseur, of Chicago, Illinois, for an improvement in "Envelop-Sealing and Stamp-Affixing Machines," an error appears in the printed specification requiring correction as follows: Page 10, line 21, the word "feeder" should read *feeler*; and that the said Letters Patent should be read with this correction therein that the same may conform to the record of the case in the Patent Office.

Signed and sealed this 8th day of February, A. D., 1910.

[SEAL.]

E. B. MOORE,

Commissioner of Patents.

pile of envelops, means for feeding envelops successively from said support along a pre-determined path by a continuous movement, a support for a sheet of stamps consisting of a plurality of rows of stamps and a plurality of stamps in each row, means for severing the stamps of said sheet and feeding them successively along a path intercepting said path, a pair of rollers located at the junction of said paths, one on either side of the envelop path and adapted to roll the

stamps upon the envelops, and means actuated by the envelops for controlling the feeding of the stamps, substantially as described.
